CLAIM

I claim the ornamental design for a shoe, as shown and described.

DESCRIPTION

FIG. 1 is a front perspective view of a shoe, showing my new design;

FIG. 2 is a right side view thereof;

FIG. 3 is a rear perspective view thereof; and,

FIG. 4 is a rear view thereof.

The dot-dash broken line represents a boundary of the claimed design and forms no part thereof. The broken lines depicting the remainder of the shoe show features that form no part of the claimed design.
